ATTORNEY.

UNITED STATES PATENT OFFICE.

JOSEPH W. REID, OF PATERSON, NEW JERSEY.

BOBBIN.

1,243,102.

Specification of Letters Patent. Patented Oct. 16, 1917.

Application filed May 3, 1917. Serial No. 166,077.

To all whom it may concern:

Be it known that I, JOSEPH W. REID, a citizen of the United States, residing at Paterson, in the county of Passaic and State 5 of New Jersey, have invented certain new and useful Improvements in Bobbins, of which the following is a specification.

In a certain class of bobbins it is exceedingly desirable that they combine lightness 10 with sufficient strength to withstand any rough usage to which they are likely to be put; this is true especially of bobbins from which the thread or yarn is drawn in a manner involving the rotation of the bobbin 15 25 in response to the draft on the thread, and where the thread is so tender that the resistance of the bobbin to rotation is sufficient to cause its breakage.

My invention contemplates providing a 20 bobbin which shall be lighter than bobbins ordinarily used and as strong as, if not stronger than, the same. According to my invention, the barrel is made of tubular paper material and the heads of wood or other suitable material, the ends of the barrel being in-set in the heads, after which the 25 whole is given a liquid surface treatment that not only stiffens up and hardens the paper but on hardening closes up all seams 30 and eradicates all roughness which might otherwise catch the thread, especially the delicate fibers of silk, and lead to breakage thereof; this treatment in its preferred form consists in first oiling the surfaces of the 35 barrel and heads, which softens and lays the fibers, and then applying a hardening liquid coat or coats, as of paint first and shellac afterward, so that the result will be a hard, smooth film distributed, un- 40 broken, over the entire exposed surface of the bobbin.

In the accompanying drawing,

Figure 1 is a side elevation of a bobbin 45 constructed in accordance with my invention and showing the different layers of the coating as I prefer to apply it;

Fig. 2 is a sectional view on the line 2—2 of Fig. 1;

Fig. 3 is a sectional view on the line 3—3 50 of Fig. 1;

Fig. 4 is an enlarged fragmentary sectional view; and

Fig. 5 shows in longitudinal section a 55 modified form of the bobbin.

a designates the heads of the bobbin, the same being preferably of wood or some other

suitable material that can be turned in a lathe and is suitable for the purpose and each having an inwardly projecting cylindrical boss *b* and a peripheral flange *c*; 60 the boss projects inwardly of the flange, the same as in other bobbin heads which are formed separately from the bobbin barrels, and the outer face of the head is flat. Each head is penetrated by the usual spindle 65 hole *d*.

The barrel *e* is composed of a suitable length of paper, card-board, straw-board or other substantial material (herein designated "paper").

Concentric with and concentrically abutting on the periphery of the boss *b* each head is formed at the inner side with a groove *f* the width of which is exactly the same as the thickness of the barrel *e*. Each 75 end of the barrel is fitted into the groove of each head, being held therein by applying to the surfaces of the grooves and the ends of the barrel a suitable adhesive, such as glue.

By forming the bobbin in this manner, I obtain exceeding lightness. For stiffening the barrel and very materially increasing the strength thereof, so that to all intents and purposes it shall be quite as strong as 85 if formed of a thicker and heavier piece of wood, and for laying all roughness and closing up interstices and seams in which the fibers of the silk or other thread might catch, I treat the bobbin thus formed as 90 follows:

I first coat the bobbin all over, or at least as to so much of the surfaces of the barrel and heads as has contact with the thread package, exteriorly with oil, as linseed oil. 95 This has the effect of not only softening but laying the fibers of the wood and paper which might otherwise project, stiff enough to catch and hold the fibers of the thread and injure the same. Having thus prepared a surface which is smooth and without roughness of any kind on which the thread might catch, I treat the surface so as to make it hard and give stiffness to the barrel, preferably using material that will more or less impregnate the oiled surface and will set, leaving a hard film coating said surface. To this end, I preferably first apply a paint coat or coats over the oiled coat, and then when that has dried apply a 105 coat of shellac. In Figs. 1 and 4, the oiled coat is indicated at *g*, Fig. 4 showing the 110

oiled coat as impregnating the surfaces of the barrel and head; the paint coat is indicated by *h*, appearing as a broken line in Fig. 4; and the coat of shellac is indicated by *i*, being a solid line in Fig. 4. The result is not only a hard, smooth finish and a coating which extends continuous over the joints between the several parts, but a very appreciable hardening and stiffening of the barrel, so that although it is made of paper it is in fact appreciably stronger than the barrel would be if composed of a materially thicker body of wood, with the very important advantage that the bobbin as a whole is very much lighter than a bobbin composed wholly of wood.

In the larger sizes of bobbins I may reinforce the middle part of the barrel substantially the same as wooden barrels are frequently reinforced. Thus in Fig. 5, *j*

is a reinforcing disk glued in the barrel midway between the heads and having a central aperture *k* to admit the spindle.

Having thus fully described my invention, what I claim as new and desire to secure by Letters Patent is:—

A bobbin including a pair of heads of fibrous material forming peripheral flanges on the bobbin and a barrel of fibrous material having its ends jointed and secured to the heads, the bobbin having a coating extending continuous over the several surfaces of the heads and barrel and which at its inner side impregnates said surfaces and is fiber-softening and fiber-laying and at its outer side is for its whole extent stiff, hard and smooth.

In testimony whereof I affix my signature,

JOSEPH W. REID.
